(57) **CLAIM**

The ornamental design for a detergent pouch, as shown and described.

DESCRIPTION

FIG. 1 is a perspective view of a detergent pouch, showing our new design;

FIG. 2 is a front view thereof;

FIG. 3 is a side view thereof;

FIG. 4 is a back view thereof;

FIG. 5 is an opposite side view thereof;

FIG. 6 is a top plan view thereof; and,

FIG. 7 is a bottom plan view thereof.

The evenly spaced broken lines illustrate portions of the detergent pouch and form no part of the claimed design. The dot-dash-dot broken lines illustrate the bounds of the detergent pouch and form no part of the claimed design.
